(57) **CLAIM**

The ornamental design of a dog device, as shown and described.

DESCRIPTION

The copyright and trade dress owner reserves all copyright and trade dress rights whatsoever.

FIG. 1 is a top and left perspective view of a dog device;

FIG. 2 is a rear view thereof;

FIG. 3 is a right view thereof;

FIG. 4 is a left view thereof;

FIG. 5 is a top view thereof;

FIG. 6 is a front view thereof; and,

FIG. 7 is a bottom view thereof.

The broken lines shown in the drawings represent portions of the dog device that form no part of the claimed design.
